Primary Examiner — Shannon W Morgan*Assistant Examiner* — Altaira J Swangin(74) *Attorney, Agent, or Firm* — Schwabe Williamson & Wyatt(57) **CLAIM**

We claim the ornamental design for a headlamp, as shown and described.

DESCRIPTION

FIG. 1 is a perspective view of a headlamp, showing our new design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The dashed lines are included for illustrating portions of the headlamp which form no part of the claimed design.
